ELECTRIC CIRCUIT CONTACTS

Thomas R. Stuelpnagel, Inglewood, and Pol R. Verbeke, Los Angeles, Calif., assignors to Hughes Tool Company, Houston, Tex., a corporation of Delaware

Application March 1, 1954, Serial No. 413,302

5 Claims. (Cl. 200—105)

This invention relates to electric circuit contact devices, and more particularly to improvements in contacts which are to be actuated by extremely small forces.

In certain types of circuit contact applications, such as sensitive relays, contacts may be required (a) to be separated by only a few thousands of an inch, (b) to be operated on less than a gram of contact pressure, (c) to be capable of extended use, and (d) to need little or no attention. To meet such demands, a primary cause of contact failure which must be overcome is the formation of spires which attends the transfer of metal to the positive contact when the contacts are separated.

In many prior art circuit contact devices, protective circuits are connected between the contacts to suppress arcing and sparking when the contacts are separated. This provision is effective to reduce the volume of metal transfer, but it does not prevent the formation of slender spires, which lengthen progressively with the number of make-and-break operations. These spires may ultimately form a link between the contacts which cannot be broken with the force available, and this possibility necessitates frequent inspection and maintenance to keep the contacts in operation. It is for these reasons that, in many instances, bulky and costly electronic amplifying systems must be relied on to develop the power required to control electric circuit operations.

The present invention overcomes the above-mentioned disadvantages and provides means whereby sensitive contacts may be employed where great reliability of operation is required and where available space for necessary electrical components is at a premium. In accordance with this invention, a cylindrical contact surface is continuously or intermittently rotated. A movable contact is spaced from the periphery of the rotating contact, against which it may be brought into engagement. Bearing against the periphery of the rotating contact is an element for keeping the surface of the rotating contact smooth and clean, which element causes a continuous shearing action against the cylindrical contact surface when the latter is rotating, to thereby substantially reduce build-up of metal transfer and prevent spire formation.

It is, therefore, an object of this invention to provide rotatable circuit contact means capable of reliable operation over a long operating life by continuously removing spires formed by contact actions, and which contact means is suitable to be controlled with a minimum amount of power.

It is another object of this invention to provide electric circuit contact means comprising a minimum number of component parts of simple design, capable of providing reliable operation without attention, and with which sensitive contact operation over a long contact life is realized.

The invention, both as to its organization and method of operation, together with further objects and advantages thereof, will be better understood from the following description considered in connection with the accompany-

2

ing drawings, in which preferred embodiments of the invention are illustrated by way of example. The scope of the invention is pointed out in the appended claims: In the drawings:

5 Fig. 1 is a perspective view of electric circuit control apparatus employing contact means in accordance with this invention; and

Fig. 2 is a modification of the arrangement shown in Fig. 1.

10 Referring to the drawing, in which like reference characters indicate like parts throughout, and referring more particularly to Fig. 1, a control circuit 10 is connected to the terminals 12 of an electromagnet 14. The electromagnet 14 is provided with a movable armature 16. An electric circuit contact arm 18 having a contact portion 21 is affixed to or integral with armature 16 for movement therewith when electromagnet 14 is energized.

15 Contact arm 18 is positioned such that contact portion 21 is adjacent the cylindrical contact surface 20 of a rotary contact element 19. A spring 17 is attached to the armature 16 and the frame of electromagnet 14 to normally bias the member 18 out of contact with the surface 20. When armature 16 is attracted by electromagnet 14, contact 21 is brought into engagement with surface 20. Element 19 is preferably a slip-ring type of contact and is supported on and insulated from the shaft 22 of a motor 24.

20 Bearing against surface 20 is a contact 26 which is a spring metal element arranged to maintain constant shearing engagement against surface 20. When a circuit is connected between contact 26 and contact 18, and when electromagnet 14 is energized to bring contact 21 to bear upon surface 20, rotation of element 19 by motor 24 causes a shearing action by contact 26 which action 25 prevents the aforementioned spire build-up by scraping off any minute metal particles that are deposited on surface 20 from contact 18.

25 A load circuit 28 and a power source, indicated as a battery 30, are serially connected between contact 26 and contact arm 18. Motor 24 may be supplied with energy either from battery 30 or from a separate power source 32, as indicated schematically in the drawing by the provision of a switch 34 for selecting the source of energy for driving motor 24.

30 40 A conventional contact protection circuit 35 is connected between the contact 26 and contact arm 18. Circuit 35 is designed to give maximum protection against arcing and sparking which the particular load circuit 28 tends to cause.

45 Fig. 2 illustrates a modification of the arrangement above described, including power relays controlled by a sensitive relay for alternatively energizing two control circuits and for performing the function of the motor 24 of Fig. 1. Referring to Fig. 2, a second rotary contact element 19' is supported on shaft 22 and spaced from element 19. A movable contact arm 18' having a contact portion 21' fixed to armature 16, is positioned

50 such that contact 21 is adjacent the peripheral surface 20' of element 19'. Armature 16 is arranged for actuation in opposite directions by a polarized electromagnet 14'. When armature 16 is moved in one direction, contact 21 engages surface 20, and movement of the armature in the opposite direction causes contact 21' to engage the surface 20'.

55 60 A contact 26' bears against the peripheral surface 20' of element 19' to perform the same function as above described for contact 26 in Fig. 1.

65 Contacts 21 and 21', rotary elements 19, 19' are connected between the respective windings of a pair of power electromagnets 48, 48', and a source such as a battery 30. The power electromagnets 48, 48' are provided with

respective armatures arranged to actuate relatively large power contact assemblies 50.

A pair of ratchet wheels 42, 42' are secured to the shaft 22. Pawls 44, 44' are supported on armatures 46, 46' of electromagnets 48, 48', in engagement in the ratchet wheels 42, 42', respectively.

When electromagnet 14' is energized to cause contact 21 to engage surface 20, coil 48 attracts armature 46, causing pawl 44 to rotate ratchet wheel 42. This rotates element 19 to achieve shearing action between the contact 26 and surface 20 for removing any microscopic spires resulting from the engagement of contact 21 with surface 20. Reversal of current through coil 14' causes armature 16 to move in the opposite direction, whereupon contact 21 disengages surface 20 and contact 21' engages surface 20'. Electromagnet 48' is thus energized to attract armature 46' and pawl 44' to rotate ratchet wheel 42' and cause a shearing action between contacts 26' and surface 20'.

The power contacts 50 are connected to control the energization of an appropriate utilization device such as a power load 52. By this arrangement, the sensitive relay 14' energizes the power relays 48, 48' to control substantially any desired amount of power.

In one practical arrangement of the above-described contact structure, the separation of contact 21 from surface 20 is .002" when the electromagnet 14 is deenergized. The surface of contact 21 is .020" in diameter. The spring 17 was adjusted to provide approximately three grams of force to separate contact 21 from surface 20. This embodiment with member 19 rotated at approximately three revolutions per minute, performed more than 20,000,000 cycles of make-and-break operations without substantial change in the physical condition of the contact surfaces and without the necessity of cleaning or other attention.

From the foregoing description, it will be apparent that the present invention provides an improved type of electrical contact device particularly suitable for sensitive contact operation, presenting substantially no maintenance problems, and capable of a degree of reliable operation heretofore obtainable only with considerably more bulky and costly electronic amplifying systems.

What is claimed is:

1. A sensitive contact system for energizing an electrical circuit from a low power control circuit, said contact system comprising: a rotatably supported cylindrical contact having a peripheral surface; a movable contact constructed and arranged such as to make and break contact with said peripheral surface; first means energizable by the low power circuit for actuating said movable contact; second means responsive to actuation of the movable contact for rotating the cylindrical contact; and a resilient element having an end portion in shearing engagement with the peripheral surface of said cylindrical contact such that said shearing engagement is effective, when the cylindrical contact is rotated, for scraping off metal deposited on the peripheral surface as a result of the movable contact making and breaking contact with the cylindrical contact.

2. A sensitive contact system for energizing an electrical circuit from a low power control circuit, said contact system comprising: a rotatably supported cylindrical contact having a peripheral surface; a movable contact constructed and arranged such as to make and break contact with said peripheral surface; a resilient element having an end portion in electrically conductive but shearing engagement with said peripheral surface such that rotation of the cylindrical contact is effective for scraping off metal deposited on said surface as a result of the movable contact making and breaking contact with cylindrical contact; a control circuit embracing electromagnetic means for actuating the movable contact; and means responsive to actuation of the movable contact for rotating said cylindrical contact, said means includ-

ing an electromagnetic element, a source of electrical energy, and an actuating circuit embracing the cylindrical contact, the movable contact, the resilient element, said electromagnetic element, and said source of energy.

3. A sensitive contact system for energizing an electrical circuit from a low power control circuit, said contact system comprising: a rotatably supported cylindrical contact having a peripheral surface; a movable contact constructed and arranged such as to make and break contact with said peripheral surface; a resilient element having an end portion in electrically conductive but shearing engagement with said peripheral surface such that rotation of the cylindrical contact is effective for scraping off metal deposited on said surface as a result of the movable contact making and breaking contact with the cylindrical contact; a control circuit embracing electromagnetic means for actuating the movable contact; first means responsive to actuation of the movable contact for rotating said cylindrical contact, said first means including an electromagnetic element adapted to rotate the cylindrical contact, a first source of electrical energy, and an actuating circuit embracing the resilient element, the movable contact, the cylindrical contact, said electromagnetic element, and said source of energy; and second means for rotating said cylindrical contact independently of the first means, said second means including a second source of electrical energy and a selectively operable switch adapted for disconnecting the electromagnetic element of the first means from the first source of electrical energy and for connecting said magnetic element to said second electrical energy source.

4. A sensitive contact system for energizing an electrical circuit from a low power control circuit, said contact system comprising: a cylindrical contact having a peripheral surface; a movable contact arranged such as to make and break contact with said peripheral surface; first means energizable by the lower power control circuit for actuating said movable contact; a ratchet wheel; a shaft supporting the ratchet wheel and the cylindrical contact such that rotation of said wheel effects rotation of said cylindrical contact; a pawl constructed and arranged for rotating the ratchet wheel; second means responsive to the actuation of said movable contact for actuating said ratchet wheel; and a resilient element having an end portion in shearing engagement with the peripheral surface of said cylindrical contact such that said end portion is effective, when the cylindrical contact is rotated, for scraping off metal deposited on the peripheral surface by the contact making and breaking action of the movable contact with said peripheral surface.

5. A sensitive contact system for energizing an electrical circuit from a low power control circuit; said contact system comprising: a rotatably supported cylindrical contact having a peripheral surface; a movable contact constructed and arranged such as to make and break contact with said peripheral surface; a resilient element having an end portion in electrically conductive but shearing engagement with said peripheral surface such that rotation of the cylindrical contact is effective for scraping off metal deposited on said surface by the contact making and breaking action of the movable contact with said surface; a control circuit embracing electromagnetic means for actuating the movable contact; and means responsive to actuation of the movable contact for rotating the cylindrical contact, said means including a ratchet wheel, a shaft supporting the ratchet wheel and the cylindrical contact such that rotation of said wheel effects rotation of the cylindrical contact, a pawl constructed and arranged for rotating the ratchet wheel, an electromagnetic element adapted for actuating said pawl, a source of electrical energy, and an actuating circuit embracing the resilient element, the rotating contact, the movable contact, the electromagnetic element, and the source of electrical energy.
